UNITED STATES PATENT OFFICE.

LEWIS J. BAZZONI, OF SWAMPSOFT, MASSACHUSETTS, ASSIGNOR TO UNITED SHOE MACHINERY CORPORATION, OF PATERSON, NEW JERSEY, A CORPORATION OF NEW JERSEY.

BUTTON-LOCATION-MARKING MACHINE.

Application filed March 29, 1920. Serial No. 369,737.

To all whom it may concern:

Be it known that I, LEWIS J. BAZZONI, a citizen of the United States, residing at Swampscott, in the county of Essex and State of Massachusetts, have invented certain Improvements in Button-Location-Marking Machines, of which the following description, in connection with the accompanying drawings, is a specification, like reference characters on the drawings indicating like parts in the several figures.

The present invention relates to the marking of shoe uppers and analogous articles, and is herein described in connection with the marking of button locations upon such articles.

In the accompanying specification the invention is shown in its application to the marking of shoe uppers, but it is to be distinctly understood that it is in no way limited thereto. As a matter of convenience, the term "shoe upper" is used throughout the specification to designate the article marked, but this is for purposes of illustration only and, except where the context or limitations imposed by the prior art necessitate a more limited construction, that term is intended to cover also any analogous articles, such, for example, as gaiters, capable of being marked as set forth.

It has been heretofore proposed to utilize the finished buttonholes of a shoe fly, which has been stitched to the quarters and then folded so that the fly properly overlaps the button quarter, as a guide in marking the button locations of a shoe. Difficulty is experienced, however, when so marking button locations in providing a mark which is reasonably permanent and at the same time will not damage the stock. A puncture or indentation will close up and disappear and a chalk mark will often rub off so that when the time arrives to utilize the mark, it is not visible. An ink mark has a tendency to spread, particularly in cloth and canvas, and therefore is likely to be inexact, and moreover, the appearance of the upper is injured by the spreading ink, while the difficulty of passing a cauterizing marker through a buttonhole without injury thereto is readily apparent.

An object of my invention, accordingly, is

to mark shoe uppers and analogous articles with a mark which will be definite in location, sufficiently permanent to withstand the treatment to which a shoe upper is ordinarily subjected, and which will in no way damage the stock on which it is placed. One way in which this may be accomplished is by the use of small markers of adhesive material stuck to the stock in the desired locations. Such markers of adhesive material may conveniently be stuck to the button quarters of shoes which have been folded with their buttonhole flies properly overlying their button quarters by passing the markers through the buttonholes and pressing them into adhering contact with the button quarters beneath, though it is to be understood, of course, that my invention in many of its aspects is not limited to the placing of the marks in this manner.

These marks may consist, for example, of small disks of gummed paper, of a size to pass readily through the eyes of the buttonholes. White paper will provide marks contrasting nicely with any stock except white or very light colored, in which case black or any dark colored paper will be found effective. Such a disk of moistened gummed paper or other small piece of adhesive material may readily be cut from a sheet or strip by a punch and carried through the buttonhole and pressed into adhering contact with the stock folded beneath by the punch and without removal from the end surface thereof until in its final position on the shoe upper.

When the article to be marked is made of a fabric, a strip of transfer paper may be substituted for the strip of adhesive material. If ordinary carbon paper is used it will not, of course, be moistened. When carbon paper is so used the disk will not stick to the fabric but the coating of the carbon paper will adhere to the fabric and make the desired mark.

In one of its aspects, the invention comprises a method of marking shoe uppers characterized by pressing portions severed from a piece of marking material into contact with the shoe uppers to be marked. In one of the exemplifications of the specification these portions may consist of disks of

moistened gummed paper, cut by a punch from a strip, and carried by the punch through the eyes of the buttonholes and pressed by it into adhering contact with the 5 button quarter folded beneath.

The invention also includes within its scope, and in another of its aspects comprises, a machine constructed and arranged to mark shoe uppers with a marker of 10 adhesive material pressed into adhering contact therewith.

In the machine aspect of the invention, a feature thereof consists in the combination with button location marking means of buttonhole entering feeding means, either with 15 or without means for operating said marking and feeding means a selectively predetermined number of times.

A further feature of the invention consists 20 of the provision in a marking machine, of means for utilizing the spacing of the buttonholes to control the feed of the shoe upper, so that at the conclusion of each feeding movement a buttonhole will be 25 located in alignment with the marking member.

A further feature of the invention consists 30 of a novel construction of means for moistening the adhesive material, such as a strip of gummed paper, from which the marking pieces are thereafter cut.

A further feature of the invention consists 35 of a novel construction of edge gage, adaptable to position correctly either a right or a left shoe upper as the upper is fed to and past the marking element.

In still another aspect, my invention comprises a shoe upper marked as above set forth.

40 These and other features and advantages of the invention are more fully described in the following specification and illustrated in the accompanying drawing in which,

45 Fig. 1 is a side elevation with parts broken away and parts in section more clearly to show the operating portions of a machine in connection with which the invention will be described;

50 Fig. 2 is a front elevation, with the front cover plate removed and with certain parts in section;

55 Fig. 3 is a perspective view of the feeding and marking elements and some of their associated parts at the front end of the machine;

Fig. 4 is a side elevation of the lower portion of the part of the machine shown in Fig. 3;

60 Figs. 5, 6, 7 and 8 are detail views of a portion of the driving mechanism of the machine, including a counting mechanism arranged to stop the machine after a variably predetermined number of marks have been made;

65 Fig. 9 is a longitudinal section through

the marking tool, the strip moistening roll, and the work; and

Fig. 10 is a diagrammatic view of a portion of a shoe upper the button locations on which have been marked by this machine. 70

The machine of the drawings is provided with a hollow base portion 20 which houses the mechanism of Figs. 5 to 8, inclusive, and carries an upwardly and forwardly extending arm 22 provided at its forward end with a head or housing 24 having a removable cover plate 25. Journalled in bearings 26 at the rear of the machine is a shaft 28 provided at its upper end with a bevel gear 30 meshing with a similar bevel gear 32 carried at the end of the shaft 34. This shaft extends horizontally through the arm 22 and is journalled near its ends in suitable bearings carried thereby.

Carried by shaft 34 is a cam 36 provided with a groove which receives a roll 38 carried by the lower end of a lever 40, the latter being fulcrumed at 42 to the interior of arm 22. Connected to lever 40 by a pivot concentric with the roll 38 is a link 44 connected at its other end to a bell crank lever 45 having arms 46 and 48. This bell crank lever is pivoted at 50 to a lever 52 which is fulcrumed at 54 to the interior of arm 22, depending therefrom and pivotally carrying at its lower end, as will be more fully hereinafter described, a work feeding finger 56 provided with a finger hold 57. The arm 48 of the bell crank lever 45 carries at its end a roll 58 engaging the slot of a slotted member 60 which is pivoted at 62 to the arm 22 and is normally held in the position shown in Fig. 1 by a spring 64 attached at one end to the side wall of arm 22 and at the other end to member 60, and tending to hold member 60 in contact with a suitable stop 65.

The work feeding finger 56 is provided at its forward end with a down turned portion 66 adapted to enter a buttonhole of the stock to be marked to move the latter rearwardly. Co-operating with the finger 56 is a second work engaging finger 68 pivoted at 70 to a lug carried by the interior of the base 20 and provided with an arm 72 connected by a link 74 to an arm 75 of a rock shaft 76, this latter being connected also by an arm 77 and a link 78 to the lever 52, the arrangement being such that the work feeding finger 68 partakes of exactly the same forward and rearward movements as the finger 56.

The shaft 34 carries at its forward end a cam member 80 having on its opposite faces cam grooves 82 and 84. To co-operate with the work feeding finger 56 and to hold the work against undesired movement during the marking operation, a presser foot 86 is provided, pivotally carried and spring held as at 87 at the lower end of a reciprocable slide member 88 which is re-

ciprocated in a suitable guideway through movement of a roll 90 carried at its upper end and received in the cam groove 82. Carried by the slide member 88 and reciprocating therewith is a curved stop 92 so situated that as it reaches the lowermost portion of its downward movement it will contact with a lug 94 carried by one end of a small rock-shaft 96 (see Fig. 4) which carries at its other end an arm provided with a roll 98 positioned to engage with a cam surface 100 of the feed finger 56 so that as the presser foot 86 moves into work engaging position, the rockshaft 96 will rock the roll 98 upwardly to lift the work finger 56, which is then to the rear of the position shown in Fig. 1, to move the down turned end 66 of the finger 56 from work engaging position.

It may be noted here that the work, consisting, for instance, of a shoe upper with the buttonhole fly folded over the button quarter, as indicated in Fig. 9 and in the lower portion of Fig. 10, is placed upon the work support of the machine with the edge of the buttonhole fly in engagement with one side or the other, according as the upper is a right or a left, of the edge gage 102 (see Fig. 3). The end 66 of finger 56 is arranged to enter the successive buttonholes and, bearing against the button quarter in opposition to finger 68, move the work step by step towards the rear of the machine as the successive marks are applied to the button quarter through the buttonholes, as will be hereinafter described.

The machine is arranged to feed the work rearwardly step by step, the length of the different steps being controlled by the distance between the successive buttonholes of the work, as will now be described. After the finger 56 is moved upwardly to remove its end 66 from the buttonhole it moves forward under the control of the mechanism above described and under the influence of cam 36. At its rear the finger 56 is provided with an extension or arm 104 connected to one end of a spring 106 supported at its other end by a lever 108 pivoted at its far end, as seen in Fig. 1, to the interior of arm 22 and carrying a roll 110 bearing upon a cam 112 carried by shaft 34. This spring tends normally to press the end 66 of finger 56 lightly against the work. As the finger 56 moves forwardly the low portion of the cam 112 bears against the roll 110 so that the tension of the spring 106 is but little and the friction between the work and the feeding fingers 56 and 68 is inappreciable. At this time, of course, the presser foot 86 is held by its cam in its lowest position so that it thus holds the work against undesired movement. When during its forward movement the downwardly turned end 66 of finger 56 enters a buttonhole, it is lowered

into contact with the upper surface of the button quarter by the action of spring 106 and the resistance to further forward movement of the finger 56 occasioned by the entry of the end 66 into a buttonhole is sufficient to rock the slotted member 60 clockwise as viewed in Fig. 1 against resistance of its spring 64 so that the bell crank lever 45 rocks in a counter-clockwise direction, as viewed in Fig. 1, about its pivot, thus permitting the finger 56 to remain stationary even though it has not reached the extreme forward position to which it is capable of being moved. When the cam 36 thereafter starts the rearward movement of link 44, bell crank 45 is first rocked to the position shown in Fig. 1, and thereafter moves the lever 52 and work feeding fingers 56 and 68 rearwardly until the buttonhole is placed in marking position, whereupon the cycle of movement is repeated as long as the machine remains in operation. During the rearward work feeding movement of the fingers 56 and 68, the rise of cam 112 elevates lever 108 so as to increase the tension of spring 106 to grip the work securely between the ends of the fingers 56 and 68. It will thus be seen that as the work is fed rearwardly the spacing of the buttonholes is utilized to control the feed of the work.

Marking mechanism is provided to place marks upon the button quarter to indicate the proper position for the different buttons. This is accomplished by marking means arranged to pass through the successive buttonholes and place marks upon the button quarter beneath. For this purpose, the machine is provided with a pair of supports 120 for a strip of marking material, such as gummed paper or carbon paper, illustrated in Fig. 1 as wound into a roll 122 carried by a shaft 124 held in suitable notches 261 of the supports 120. From the roll 122 the strip passes over a guide roll 126, through an eye 128, and through a slot 130 of a sleeve 132 (see Fig. 2) serving as a guideway for the strip and mounted in the head of the machine for reciprocation. The sleeve 132 is reciprocated by the cam groove 84 engaging a roll 144 on a bar 145 attached to the sleeve. Sleeve 132 is reduced at its lower end so as conveniently to pass through the eye of a buttonhole and guide the marking disk which is cut out to the exact location desired. Carried within the sleeve 132 for reciprocation relatively thereto is a plunger 140 carrying at its lower end a marker such as a solid punch 142. The plunger 140 is rotatably connected to a sliding head 138 having a curved slot 136 engaged by a crank pin 134 on the cam member 80. As indicated in section in Fig. 2, the upper end of the plunger 140 has a cupped portion 146 to receive a grooved ex-

tension 147 depending from the sliding head 138, there being a pin 148 in the cup of the plunger extending into the groove of the extension thereby to raise and lower the plunger without interfering with rotary movement. The crank pin 134 and groove 84 are so arranged that the plunger 140 is reciprocated through a longer path than that of sleeve 132, the two parts being so related that as the sleeve and plunger move upwardly, the lower end of the punch 142 passes to a position above the slot 130 and as the two move downwardly the punch cuts a disk from the strip of paper passing through slot 130, carries it downwardly and when the lower end of the sleeve 132 enters the buttonhole which is then positioned therebeneath, the punch 142 presses the disk of paper which it carries firmly against the button quarter of the shoe to be marked. The plunger is moved through a path of greater amplitude than the sleeve because its stroke is equivalent to twice the distance of the crank pin 134 from the axis of shaft 34 whereas the stroke of the sleeve is determined by the difference in the distances between the axis of shaft 34 and the high and low points respectively of the cam 84.

Suitable means may be provided for feeding the strip of marking paper through the machine and this is shown as consisting of a pair of feed rolls 150 and 152, the former being journaled in a spring-held bracket 154 carried by arm 22 and the latter in a bracket 156. The roll 152 has formed rigidly therewith a ratchet 158 co-operating with a spring-held pawl 160 pivoted as at 162 to a lever 164 carried by bracket 156 and provided with a roll 166 bearing against a cam surface 168 carried by the lower end of a lever 170. This lever is pivoted at 172 to the arm 22 and is connected by a link 174 with lever 40 so that as lever 40 is oscillated by cam 36, the lever 170 is also oscillated to operate the pawl 160. This results in feeding the strip of paper in a step by step manner in timed relation to the operation of the marking means. A suitable guide 176 may be provided to direct the paper strip between the rolls 150 and 152. 178 indicates a spring pawl co-operating with the ratchet 158 to prevent backlash.

Where the material to be marked is a textile fabric, such for instance as that used in the manufacture of gaiters, a strip of marking material consisting of carbon paper may advantageously be used. In that case, the punch 142 will remove a disk of carbon paper from the strip and press it firmly against the gaiter whereupon the coating from the disk of paper will adhere to the gaiter and form a mark thereon. When the machine is operated in this manner, its effectiveness may be increased by providing means for rotating the punch 142 so that

the coating of the carbon paper will be ground into the surface of the material. This rotation of the punch also serves, when an adhesive strip is used, to rub the pill cut from the strip and force the paste or glue into intimate contact with the fibres of the material. For this purpose in Fig. 2 the plunger 140 is shown as provided with a spiral groove 180 for co-operating with a pin 182 carried by the sleeve 132.

Where the stock to be marked consists of leather such as that commonly used for shoe uppers, the strip of marking material may advantageously consist of gummed paper. When this is used, the machine is provided with moistening means as shown in Figs. 1 and 3. This may consist of a receptacle 184 for water, the same being provided with an outlet such as a nozzle 186 and with any suitable means, indicated at 188, for controlling the passage of the water from the receptacle drop by drop. The means for this purpose indicated in Figs. 1 and 3, consists of an ordinary valve and a controller therefor such as is commonly used to control the application of lubricating oil to various types of machinery and a detailed description of the same is thought to be unnecessary. From the nozzle 186 the liquid passes through a pipe 189 to a hollow cylinder 190 (Figs. 1, 3 and 9). Loosely journaled on a shaft 192, above the cylinder and loosely fitting within a slot 194 in the upper wall of the cylinder is a disk or roll 196 somewhat narrower than the strip of paper and positioned to contact therewith as indicated in Fig. 9. The roll 196 carries a film of liquid from the cylinder 190 and applies it to the strip of gummed paper from which the marking disks are to be punched. The punch 142 passing downwardly through the moistened strip of gummed paper cuts a disk therefrom and carrying it down through the buttonhole presses it into adhering contact with the button quarter successively to mark the different button locations.

Co-operating with the punch 142 there is provided a plunger 198 held by a spring 200 in the position shown in Figs. 1 and 3 and arranged to yield under the impact of the punch 142 to prevent injury to the stock thereby. Adjacent to this plunger the work support 202 of the machine is provided with a projection 204 to co-operate with the presser foot 86 in holding the work in position.

It will be evident that in order to position the work with the buttonhole fly above the button quarter, the edge of the buttonhole fly will be presented to the right or to the left according to whether the shoe upper to be marked is a right or a left, the upper being presented to the machine with the eye of the buttonhole away from the operative as viewed in Fig. 1. To assist in so presenting

the work to the machine, the edge gage 102 is made in the form of a letter H with the cross-bar thereof arranged vertically so that the edge of the buttonhole fly may engage one side or the other of the cross-bar of the H according as the shoe upper is a right or a left. This edge gage is carried by an arm 206 pivoted at 208 to a plate 209 adjustably carried, as by a screw and slot connection 10 213, by the head of the machine and is provided at its upper end and adjacent to its pivot with a pair of arms 210 arranged alternatively to engage one or the other of a pair of lugs 212 carried by the plate 209. Thus 15 the edge gage 102 may be moved to one side or to the other of the end 66 of the work feeding finger 56 as the situation demands. Mechanism will now be described by means 20 of which the machine may be controlled to complete a variably predetermined number of cycles of operation and then stop. For example, if the shoe upper is provided with fourteen buttonholes, the machine may be set to operate through fourteen cycles of 25 operation, to apply fourteen marks and thereupon come to rest. For this purpose, within the hollow base of the machine a shaft 220, provided with a bevel gear 221 meshing with a similar gear carried by the lower end of 30 shaft 28, is journaled in bearings 222. Loosely on this shaft and driven from any suitable source of power, as through bevel gears 224 and 226, is a hollow clutch element 228 provided with one or more lugs 230 within the 35 cavity thereof. Mounted fast on the shaft 220 is a clutch member 232 provided with a bore 234 forming a guide for a clutch pin 236. This pin is shown in its inoperative position in Fig. 1. It is arranged to be 40 moved out of engagement with the lugs 230 by means of a wedge-shaped cam 238 slidably mounted with respect to clutch member 232 and by which it is carried. It will thus be seen that the movement of the cam 238 45 longitudinally of shaft 220 will throw the clutch into and out of operation.

To control this movement of cam member 238, the machine is provided with an element such as a treadle under the control 50 of the operative and connected by a rod 240 (Fig. 5) with a lever 242 fulcrumed on a shaft 244 carried by suitable lugs in the base of the machine. Pivoted on the pin 244 there is provided a two-armed lever 246, 55 one arm 247 of which is arranged to enter the path of movement of the cam 238 to slide the pin 236 out of engagement with lug 230 to stop the machine. Pivoted at 258 (see Fig. 6) on lever 242 is a latch member 260 having one end 262 arranged to bear against a shoulder 264 formed on lever 246. A spring 266 connects at one end to the latch 60 member 260 and at the other end to lever 242, yieldingly to hold the latch in operative position.

Fulcrumed on a shaft carried by suitable bearings 270 carried by the base of the machine is a two-armed lever 272, one of the arms 274 of which is in position to engage with a lug 276 carried by an arm of lever 246. Thus when the lever 242 is depressed as by the operation of the treadle, the latch 260 operates to swing the lever 246 in counter-clockwise direction as viewed in Figs. 5 and 6, so as to withdraw its arm 247 from engagement with the cam member 238. Thereupon that member and the pin 236 are moved to the left as viewed in Fig. 1 by a spring 278 housed in a hole formed in clutch member 232 and bearing against a small pin 279 carried by pin 236 to start the operation of the machine. As the lever 242 is rocked downwardly and after its arm 247 is moved from the path of rotation of the cam 238, an arm 280 carried by latch 260 comes in contact with an adjustable stop 282 and upon further movement of the lever 242 releases the latch 260 from the shoulder 264 of lever 246 so as to relieve the lever 246 at a given point from the influence of lever 242. Just before this happens, however, the lever 246 has moved to such a position that the lug 276 in its movement downward over arm 274 of lever 272 has passed beyond the end of arm 274 and the arm 274 has moved upwards as will be hereinafter described, so that the lug 276 of lever 246 lies below the arm 274 of lever 272, and the arm 247 of lever 246 is thus held out of the path of movement of cam 238. Accordingly the machine will continue to operate until the arm 274 is rotated downwardly to such an extent that lug 276 can pass upwardly thereover. To control the position of arm 274 the lever 272 is provided with an arm 284 carrying a roll 286. A spring 288 (see Fig. 8) operating against arm 290 of lever 272 normally tends to hold the roll 286 in contact with a cam 291 secured to shaft 220 and having formed rigidly therewith a ratchet 292 provided with a lug 294. Cam 291 is provided with a rise 296 and when in the rotation of the cam the rise 296 comes in contact with the roll 286, lever 272 is rocked to release lever 246 which moves in a clockwise direction as viewed in Fig. 5 under the influence of spring 298 to thrust its arm 247 into the path of movement of the cam 238 and accordingly to release the clutch. 110

Loosely mounted upon the shaft 220 is a gear 300 engaging with a rack 302 formed rigid with an arm 304 pivoted at 306 on a suitable support 308 carried by the machine base and provided with a pin 310 for engagement with one of a series of segmentally arranged holes or notches in a plate carried by the frame of the machine and provided with suitable indicating marks. Carried by gear 300 is a projection or lug 312 arranged in the path of movement of lug 294 carried by 115 120 125 130

ratchet 292. It will be apparent that by the movement of the arm 304 and by the placement of pin 310 in the appropriate opening, the position of lug 312 may be determinately varied.

Keyed to the shaft 220 is a cam 314 arranged to co-operate with a roller 316 carried by a lever 318 fulcrumed at 320 to the base of the machine and held in contact with cam 314 by a spring 322. Lever 318 is provided with an arm 324 carrying at its extremity a spring-pressed pawl 326 in operative relation to the ratchet 292. The lever 284 is provided with a spring-pressed holding dog 328 to prevent backlash of the ratchet and with a pin 330 positioned beneath the pawl 326 so that clockwise movement of the lever 284, as viewed in Fig. 8, will lift the pawl 326 from engagement with the ratchet 292 and will permit retrograde movement of the ratchet under the influence of a volutespring 332 anchored at one end to lever 318 and at the other end to the ratchet 292 and the cam 291 rigidly connected therewith. Such retrograde movement of the ratchet is limited, however, by the stop 312 in whatever position it has been set so that when the arm 284 of lever 272 has been lifted by the engagement of the rise of cam 291 with roll 286, the spring 332 will, in giving the ratchet 292 its retrograde movement to bring the lug 294 in contact with stop 312, move the rise 296 of cam 291 a variably predetermined part of a revolution. Then when the machine is again started, the cam 291 will move step by step through that part of a revolution, in the reverse direction of course, under the influence of the ratchet 292 and its operating means, until the rise 296 of cam 291 again encounters roll 286 and so lifts arm 284 and again stops the machine.

It will thus be seen that means is provided for operating the machine through a variable predetermined number of cycles of operation and thereafter stopping the machine. This means, however, is not broadly claimed per se in the present application, since a somewhat different embodiment thereof, operating, however, according to the same principles, forms part of the subject matter of and is claimed in my co-pending application bearing Serial No. 362,542, filed March 1, 1920.

The operation of the machine may be briefly outlined as follows: The driving mechanism having been set in accordance with the number of buttonholes in the shoe upper or other article to be marked, the properly folded upper is placed upon the work support of the machine with the edge of its buttonhole fly in engagement with the appropriate side of the edge gage 102 and with end 66 of finger 56 in engagement with the eye of the first buttonhole. The finger 56 may be conveniently raised for this pur-

pose by means of the finger hold 57. The machine is then started and the work fed into position for the marking of the first button location. The end 66 of finger 56 thereupon is lifted from the buttonhole by the operation of the roll 98 against the surface 100 of the work feeding finger 56 and, the work being held in position by the presser foot 86, the feeding fingers 56 and 68 move forward out of the way and the end 66 comes down against the fly at a point at the rear of the succeeding buttonhole. Then the punch 142 moves downward to cut a disk from the strip of marking material and, when the end of sleeve 132 enters the buttonhole, continues its downward movement and rotates and thereby presses the disk firmly against the button quarter beneath the buttonhole to mark the former. As the cycle of operation continues, the punch 142 and sleeve 132 move upwardly out of the way, the work feeding fingers 56 and 68 continue their forward movement until the end 66 of the former enters a buttonhole and, on account of the lost motion permitted thereto by the means transmitting the movement of link 44 to lever 52, moves no farther. On the return movement of the work feeding fingers, the work moves rearwardly until the second buttonhole is in position beneath the marking tool. The operation of the machine continues in this manner until the last button location has been marked, whereupon the machine is stopped by the movement of arm 247 of lever 246 into the path of movement of the cam 238, in accordance with the setting of lever 304.

Having described my invention, what I claim as new and desire to secure by Letters Patent of the United States is:

1. The process of marking a button location on a shoe upper which consists in cutting a piece of suitable size from a strip of marking material, pressing said piece against the shoe upper to indicate the point of attachment of the button, and feeding the upper a distance determined by a characteristic of said upper to bring the point at which it is desired to make the succeeding mark into operative position.

2. The process of marking a button location on a shoe upper in which a series of buttonholes has been formed which consists in cutting a piece of suitable size from a strip of coated paper, pressing said piece against the shoe upper to designate the desired location of a button, and feeding said upper a distance determined by the spacing of adjacent buttonholes to bring the work into position for the application of another mark to designate the location of another button which shall co-operate with the corresponding buttonhole.

3. The process of marking shoe uppers which consists in cutting a piece from a

- strip of marking material, and rotating a tool to rub the piece of material against the upper.
4. The process of marking shoe uppers which consists in punching out a piece from a strip of marking material, and moving the punch simultaneously to press and rub the material against the upper.
5. The process of marking button locations on a shoe upper having a curved outline which consists in feeding the upper intermittently over a support and during said feeding guiding said upper along said curved outline, and successively pressing a series of pieces of marking material into adhering contact with the button piece of the upper between the feeding steps.
6. The process of marking button locations which consists in arranging the material to be marked with a buttonhole overlying the desired location of a button, and pressing a piece of coated paper through the buttonhole against the stock beneath to form a mark thereon.
7. The process of marking button locations which consists in arranging the article to be marked with a buttonhole overlying the desired location of a button, and pressing a disk of coated paper through the eye of the buttonhole against the stock beneath to form a mark thereon.
8. The process of marking button locations on shoe uppers in which a series of buttonholes has been formed which consists in predetermining the button location on the upper by reference to the buttonhole with which the particular button is to cooperate, in moving a cutting tool so as first to cut a portion from a piece of coated material, second to transfer said piece of coated material into contact with the button piece of a shoe upper in said predetermined location, and third to press said piece of coated material against said button piece to indicate the point of attachment of the button.
9. The process of marking button locations on shoe uppers which consists in severing a small portion from a piece of adhesive material with a suitable instrument, guiding the severed portion to the desired location, pressing said severed portion into adhering contact with the button piece of a shoe upper by means of said instrument, and rubbing the instrument over the severed portion to facilitate adhesion.
10. The process of marking button locations on shoe uppers which consists in cutting a disc smaller than the eye of the buttonhole from a strip of adhesive material with a suitable instrument, pressing said disc into adhering contact with the button piece of the shoe upper by means of said instrument, and rotating the instrument while in contact with the attached disc to rub it into firmer contact.
11. The process of marking button locations, which consists in arranging the material to be marked with a buttonhole overlying the desired location of a button, and pressing a piece of adhesive material through the buttonhole into adhering contact with the stock beneath.
12. The process of marking button locations, which consists in arranging the article to be marked with a buttonhole overlying the desired location of a button, and pressing a disc of adhesive material through the eye of the buttonhole into adhering contact with the stock beneath.
13. The process of marking button locations, which consists in arranging the article to be marked with its buttonholes overlying the desired locations of its buttons, and pressing pieces of adhesive material through the successive buttonholes into adhering contact with the stock beneath.
14. The process of marking button locations which consists in arranging the article to be marked with a buttonhole overlying the desired location of a button, moistening a portion of a strip of gummed paper, detaching a piece of the moistened gummed paper from the strip, and pressing the detached piece of the moistened gummed paper through the buttonhole into adhering contact with the stock beneath.
15. The process of marking button locations which consists in arranging the article to be marked with a buttonhole overlying the desired location of a button, moistening a portion of a strip of gummed paper, severing a disk from the moistened gummed paper and pressing the disk of paper through the eye of the buttonhole into adhering contact with the stock beneath.
16. The process of marking button locations on a shoe upper which consists in arranging the buttonhole fly with the buttonholes overlying the desired locations of the buttons on the button fly, feeding the upper in the direction of the line of buttonholes, and passing a marking tool successively through the buttonholes into contact with the button fly.
17. The process of marking button locations on a shoe upper which consists in arranging the buttonhole fly with the buttonholes overlying the desired locations of the buttons on the button fly, and alternately pressing a piece of marking material through a buttonhole into contact with the fly and causing a relative feed movement to take place in the direction of the line of buttonholes.
18. In a shoe upper marking machine, the combination of a plunger arranged axially to reciprocate and to rotate so as to sever a portion from a piece of adhesive material and rotatively to press said portion into adhering contact with a shoe up-

per, and means to feed said shoe upper into operative relation to the severing and pressing means to present successively the locations of desired marks.

19. In a shoe upper marking machine, the combination of a punch, a pair of feed rolls to feed a strip of coated paper past the punch, means for reciprocating the punch to cut a piece from the strip of coated paper and carry it through a buttonhole of a shoe upper and into contact with a portion of the shoe upper beneath the buttonhole, and means for feeding said shoe upper to position the buttonholes and the desired locations of the buttons successively in the path of the punch.

20. In a shoe upper marking machine, the combination of a punch, means to feed a strip of marking material past the punch, means for operating the punch to cut a piece from the strip of marking material and press it into contact with the shoe upper to be marked, and means to rotate the punch as it presses the piece of marking material into contact with the shoe upper.

21. In a shoe upper marking machine, the combination of a punch, means to feed a strip of coated paper past the punch, means for reciprocating the punch to cut a disk from the strip of coated paper and carry it through the eye of a buttonhole of a shoe upper and into contact with a portion of the shoe upper folded beneath the buttonhole, and means to rotate the punch during the latter operation.

22. In a shoe upper marking machine, the combination of a punch, means to feed a strip of gummed paper past said punch, means to moisten said strip of gummed paper before it reaches said punch, means for reciprocating said punch to cut a moistened piece from said strip of gummed paper and press it into adhering contact with the shoe upper to be marked, and means to rotate said punch during its reciprocation.

23. In a button location marking machine, the combination of means to guide a folded upper in which a series of buttonholes has been formed to bring the buttonholes successively to operating position, means to moisten a strip of gummed paper, a punch, and means constructed and arranged to operate the punch to cut a small piece of moistened paper from the strip, carry it through a buttonhole in the article to be marked, and press it into adhering contact with a portion of the article folded beneath the buttonhole to designate a desired point.

24. In a shoe upper marking machine, the combination of a punch, means to feed a strip of gummed paper past the punch, means to moisten said strip of gummed paper before it reaches said punch, means axially to reciprocate and rotate said punch to

cut a moistened piece from said strip of gummed paper and press it into adhering contact with the shoe upper to be marked, and means to feed said shoe upper into operative relation to the punch to present the location of a desired mark thereto.

25. In a machine for marking button locations on a shoe upper, a marker, mechanism for causing a relative feed movement of the upper and the marker in the direction of a line of buttonholes on the buttonhole fly, said feed movement being controlled automatically by the spacing of the buttonholes, and means for causing relative movements of the upper and the marker in a direction substantially at right angles to the upper to apply a series of marks to the button fly.

26. In a machine for marking button locations on a shoe upper, a marker, feeding mechanism engaging the buttonholes on the buttonhole fly to move the upper intermittently past the marker and means for causing relative movements of the upper and the marker in another direction to apply a series of marks to the button fly.

27. In a machine for marking button locations on a shoe upper, a marker, mechanism for causing a relative feed movement of the upper and the marker in the direction of a line of buttonholes on the button fly, said feed movement being controlled automatically by the spacing of the buttonholes, and means for reciprocating the marker towards and from the button fly to apply a series of marks thereto.

28. In a machine for marking button locations on a piece of stock, a marker, mechanism for causing a relative feed movement of the stock and the marker in the direction of the line of button locations, said feed mechanism being constructed and arranged to be responsive to positions in a series of holes in a sheet of material movable with the piece of stock whereby the extent of feed movement and the spacing of the marks will be controlled by the relative position of said holes.

29. In a button location marking machine, the combination of a reciprocable marker, means for reciprocating the marker, and a buttonhole entering finger for feeding the stock between successive marking movements of the marker.

30. In a marking machine, the combination of a reciprocable plunger provided with a spiral groove and having a mark applying end, a sleeve surrounding said plunger and having a projection entering said spiral groove, means for reciprocating the plunger whereby the interaction of said spiral groove and said projection will cause said plunger to rotate, a work feeding finger, and means arranged to cause said work feeding

- finger to enter successive buttonholes and feed the work step by step into marking relation to said plunger.
31. In a button location marking machine, the combination of a reciprocable plunger having a mark applying end, means for reciprocating the plunger, means for feeding the stock between successive marking movements of the plunger a distance determined by the spacing of the buttonholes in the stock, and means for stopping the operation of said plunger and feeding means at the end of a selectively predetermined number of marking operations.
32. In a button location marking machine, the combination of a finger constructed to enter a buttonhole in the article to be marked and feed the article into marking position, means thereafter to withdraw the finger from the buttonhole, and a marker arranged to pass through the buttonhole and place a mark on a portion of the article folded beneath the buttonhole.
33. In a button location marking machine, the combination of a finger constructed to enter a buttonhole in the article to be marked and feed the article into marking position, means thereafter to withdraw the finger from the buttonhole, means to feed a strip of marking material past the marking position and a punch arranged to cut a piece from the strip and carry it through the buttonhole into contact with a portion of the article folded beneath the buttonhole.
34. In a button location marking machine, the combination of a work support, a finger constructed and arranged to enter a buttonhole in an article on said work support to feed the article into marking position, means thereafter to withdraw the finger from the buttonhole, a marker arranged to pass through the buttonhole and place a mark on a portion of the article folded beneath the buttonhole, and a presser foot operated to clamp the article to the work support while the mark is placed thereon.
35. In a button location marking machine, the combination of a marker, a feeding member constructed and arranged to enter a buttonhole in an article to be marked and feed said buttonhole into alinement with the marker, and means to move said marker through said buttonhole to place a mark on a portion of said article folded beneath said buttonhole.
36. In a button location marking machine, the combination of a marker, a feeding member constructed and arranged to enter a buttonhole in an article to be marked and move said buttonhole into alinement with said marker, and means to reciprocate said marker through said buttonhole to place a mark on a portion of said article folded beneath said buttonhole.

37. In a button location marking machine, the combination of a marker, a finger constructed and arranged to enter consecutive buttonholes in an article to be marked and feed the article past the marker, a series of steps each equal to the distance between consecutive buttonholes, and means to move said marker through the successive buttonholes to place a series of marks on a portion of said article folded beneath said buttonholes.

38. In a button location marking machine, the combination of a finger constructed to enter a buttonhole in the article to be marked and feed the article into marking position, means thereafter to withdraw the finger from the buttonhole, and a reciprocating marking member arranged to pass through the buttonhole and place a mark on a portion of the article folded beneath the buttonhole.

39. In a button location marking machine, the combination of a finger constructed and arranged to enter successive buttonholes of an article to be marked, means to reciprocate said finger to move the buttonholes consecutively into marking position, and a marking member arranged to enter each buttonhole at the marking position and place a mark on a portion of said article folded beneath said buttonholes.

40. In a button location marking machine, the combination of a punch, a sleeve surrounding said punch and forming a guide therefor and having a pair of holes in opposite sides thereof through which a strip of coated paper may be passed, and means to reciprocate said punch and said sleeve in timed relation to cut a piece from the strip of coated paper to carry it through the sleeve, to move said sleeve through a buttonhole in the stock to be marked and to press said piece against a portion of the stock folded beneath said buttonhole.

41. In a marking machine, the combination of a punch, a sleeve surrounding said punch, means to reciprocate said sleeve to bring one end into a position adjacent the piece of work, means for supplying a marker to the interior of said sleeve, and means to reciprocate said punch through a path of movement of greater amplitude than that of said sleeve to project the punch beyond the end of the sleeve so as to force said marker into contact with the work.

42. In a machine of the class described, the combination of a punch, a sleeve surrounding the punch and having an opening transversely therethrough to receive a strip of marking material, and mechanism for relatively moving the punch and sleeve to sever a piece from the strip for application to a piece of work and to move said sleeve substantially into contact with the work.

thereby to guide the severed piece of marking material into exact location with respect to the work.

43. In a machine for marking the locations of buttons upon a shoe upper in which the buttonholes have been formed, the combination of a punch, a sleeve surrounding the punch and having an opening therethrough, means for feeding a strip through

10 the opening in the sleeve, and mechanism for relatively reciprocating the punch and the sleeve to sever a series of pieces from the strip and to cause the sleeve to enter the buttonholes one after the other and thereby 15 to guide the pieces of marking material into exact location with respect to the upper.

44. In a marking machine, the combination of a marker, a sleeve surrounding the marker, means for supplying marking material to the interior of said sleeve, said sleeve and marker having a co-operating spiral groove and projection, and mechanism connected to the marker for reciprocating it within the sleeve to cause it to rotate and rub the marking material onto the work.

45. In a marking machine, the combination of a plunger having a spiral groove formed therein, a sleeve surrounding said plunger and provided with a projection entering said spiral groove, means to reciprocate said sleeve to bring its end approximately into contact with the work, and means to reciprocate said plunger through a path of movement of greater amplitude than that of said sleeve to cause said plunger to extend beyond the end of the sleeve and to rub against the work to mark the same.

46. In a marking machine, the combination of a punch having a spiral groove formed therein, a sleeve surrounding said punch and provided with a projection entering said spiral groove, said sleeve being provided with a transverse opening therethrough to receive a strip of marking material, and means relatively to reciprocate said punch and said sleeve whereby said punch is caused to rotate relatively to said sleeve to sever a piece of the strip and rub it against the work.

47. In a marking machine, a reciprocating tool, a guide for the tool, said guide and tool having a cooperating spiral groove and projection, means for reciprocating the tool in the guide from a position where its mark applying end is within the guide to a position where said end extends beyond the guide into contact with the work, means for supplying marking material to the interior of said guide below the end of said tool when in its retracted position, and a yielding work support to allow said groove and projection to effect a rotary movement of the tool after it contacts with the work.

48. In a machine of the class described, a finger having an end arranged to enter a buttonhole in a piece of stock to be operated on to move it a distance determined by the spacing of the buttonholes in the stock, a second finger positioned on the opposite side of the stock from the first finger and co-operating therewith, and means to move the second finger a distance determined by the path of movement of the first finger.

49. In a machine of the class described, the combination of a reciprocable plunger having a mark applying end, means for reciprocating the plunger to designate location points on a piece of work, a pair of work feeding fingers, operated from opposite sides of the work, and means constructed and arranged to cause said fingers to grip the work and feed it forward a variable distance determined by a characteristic of the work.

50. In a machine of the class described, the combination of a mark applying member, a pair of co-operating work feeding fingers, mechanism to cause said fingers intermittently to grip the work at a variable point determined by a characteristic of the work and feed it forward step by step, and means to operate the mark applying member to designate a location point on the work between the successive feeding movements thereof.

51. In a button location marking machine, the combination of a mark applying member, a pair of work feeding fingers, one of said fingers having a buttonhole entering end and the other finger having an end arranged to co-operate with said buttonhole entering end to grip the work between said ends, means to cause said fingers to feed the work a distance determined by the spacing of the buttonholes in the work, means to thereafter withdraw the buttonhole entering end from buttonhole entering position, and means to cause said mark applying member to enter the buttonhole from which the end of said first finger has been withdrawn to place a mark on a portion of the work folded therebeneath.

52. In a marking machine, the combination of a work-feeding finger, a marker, and means constructed and arranged to reciprocate the finger and operate the marker a selectively predetermined number of times to place a series of marks upon the work.

53. In a button location marking machine, the combination of a finger having an end shaped to enter a buttonhole in an article to be marked, a marker, and mechanism arranged to move the end of the finger into and out of successive buttonholes and to reciprocate the finger to feed the article past the marker, and to operate the marker through the buttonhole, each a selectively

predetermined number of times, to place a series of button locating marks on a portion of the article folded beneath the buttonholes.

5 54. In a button location marking machine, the combination of a punch, a feeding member constructed and arranged to enter consecutive buttonholes in an article to be marked and feed the article past the punch 65
10 a series of steps each equal to the distance between consecutive buttonholes, and means to reciprocate said punch to cut portions from a piece of marking material and press said portions through said buttonholes into 70
15 contact with a portion of said article folded beneath said buttonholes.

55. In a button location marking machine, the combination of a finger arranged to enter the successive buttonholes of an article 20 to be marked, means to reciprocate said finger to move the buttonholes consecutively into marking position, a guideway having a pair of holes in opposite walls thereof in alignment with said marking position, means 25 to feed a strip of marking material past said holes, a punch, and means to reciprocate said punch through said holes to cut pieces of marking material from said strip and press them through the successive buttonholes into contact with the shoe upper. 30

56. In a button location marking machine, the combination of a work support, a marker, a finger constructed and arranged to enter consecutive buttonholes in an article resting 35 on said work support and feed the article past the marker a series of steps equal to the distance between consecutive buttonholes, means to move the marker through the successive buttonholes to place a series of marks 40 on a portion of said article folded beneath said buttonholes, a presser foot, and operating means for said presser foot to clamp the article to the work support during the placing of said marks, and to release the article 45 for feeding movement while the finger is in engagement with the buttonholes.

57. In a machine for operating on shoe uppers, an operating tool, and means for locating an upper with respect to said tool, 50 said means comprising a movable vertical bar having opposite surfaces adapted to be selectively positioned to engage the edge of an upper and opposite horizontal extensions adapted to be selectively positioned to support the upper.

58. In a machine for marking right or left shoe uppers, a marking tool, a work support, and means for locating either a right or left upper with respect to the tool, said 55 means comprising an edge gage having a surface to position the edge of a right shoe upper and being movable so that its opposite

surface will locate the edge of a left shoe upper.

59. A machine for operating upon shoe uppers having an approximately H shaped edge gage adjustably mounted for movement so as to engage the edge of a right upper with one side of the cross-bar of the H or the edge of a left upper with the other side of the cross-bar of the H to guide said uppers into equivalent positions with respect to the operating parts of the machine. 65
70

60. A machine for operating upon shoe uppers having an approximately H shaped edge gage, said gage being pivotally mounted so that either side of the cross bar of the H may be brought into the operating path of the machine. 75

61. In a button location marking machine, the combination of a reciprocable marker, means for reciprocating said marker, means for feeding a shoe upper to the marker between successive marking movements thereof, and an edge gage adjustably mounted to engage the edge of a right shoe upper upon one side thereof or the edge of a left shoe upper upon the other side thereof to guide the shoe upper to the marking position. 80
85

62. A machine for operating upon shoe uppers having an approximately H shaped edge gage mounted at the end of a pivoted finger, the cross-bar of the H forming a continuation of said finger. 90

63. In a machine for marking button locations on shoe uppers, the combination of an approximately H shaped edge gage adjustable to position a right or a left shoe upper, buttonhole entering shoe upper feeding means, and a buttonhole entering member arranged to mark button locations on the button quarter of the shoe upper. 95
100

64. In a machine for marking button locations on shoe uppers, the combination of an edge gage adjustable to position a right or a left shoe upper, buttonhole entering shoe upper feeding means, and a buttonhole entering member arranged to mark button locations on the button quarter of the shoe upper. 105
110

65. A machine for operating upon shoe uppers having an approximately H shaped edge gage adjustably mounted for movement so as to engage the edge of a right upper with one side of the cross-bar of the H or the edge of a left upper with the other side of the cross-bar of the H to guide said uppers into equivalent positions with respect to the operating parts of the machine, and stops co-operating with said gage to determine said positions. 115
120

In testimony whereof I have signed my name to this specification.

LEWIS J. BAZZONI.
